DELAY ELECTRIC BLASTING CAP

John E. Jeffery, Shelton, Wash., assignor to Atlas Powder Company, Wilmington, Del., a corporation of Delaware

Application July 12, 1946, Serial No. 682,995

6 Claims. (Cl. 102—28)

1

This application relates to delay electric blasting caps.

An object of the invention is the provision of a delay electric blasting cap having a very short delay time.

Another object of the invention is the provision of a delay electric blasting cap having a short delay period and a low standard deviation.

A further object of the invention is the provision of delay electric blasting caps having standard deviations within relatively closely defined limits.

Other objects will be apparent from the following description.

In many multiple hole blasting operations it has been found desirable to initiate explosive charges in a number of different holes at different times, and delay electric blasting caps have been used for this purpose. A delay electric blasting cap, in addition to the customary elements of an instantaneous electric blasting cap, has usually included a train of deflagrating material located between the electric ignition element and the detonating charges in the cap. The train of deflagrating material, by the time it takes to burn, produces the desired delay period between the firing of the ignition element and the detonating charges in the initiator.

There have been two principal types of delay electric blasting caps utilized to date. Of these, one type employs a black powder delay train. Since black powder produces large quantities of gas on burning, conventional delay electric blasting caps provided with black powder delay trains additionally include vents in the shells to provide an exit for these combustion gases. To prevent premature firing of the explosive charges to be initiated by hot gases from the delay train, vented delay electric blasting caps are usually further provided with flame damping shields of various sorts.

Another type of delay electric blasting cap is the gasless type. Such initiators make use of delay trains which burn without the production of large quantities of gas and, consequently, require no vents.

Neither of these types of delay electric blasting caps has been successfully produced to give delay periods of very short duration. Most commonly they have been made in delay periods of one second or more, though some shorter fractional second delays have been made in the vented type.

When it is attempted to make vented very short delay electric blasting caps with gas producing

2

delay trains, it is found that the trains required are so short that the flame from the electric ignition element often flashes through the delay train, practically instantaneously or the delay train is blown out of position, and, in any event, no consistent delay times are obtained.

The problem is quite similar when it is attempted to make very short delay electric blasting caps of the ventless, gasless type. Such small amounts of delay powder are required that the flame flashes through the train causing instantaneous or highly ragged firing. Furthermore, delay electric blasting caps having gasless type delay trains do not ordinarily provide as consistent timing as do the vented delays having gas producing delay trains, and when it is attempted to produce short delay electric blasting caps this raggedness becomes proportionately much too high. By means of the present invention it has been found that delay electric blasting caps can be prepared, having average delay times of from about 10 to about 250 milliseconds, and standard deviations from their average times between about 6 milliseconds and about 65 milliseconds.

Delay electric blasting caps of the present invention utilize a train of propellant powder consolidated under high pressure and located inside a ventless shell. Preferably the delay train is contained in the bore of a tubular delay element located between a deflagrating ignition element and a detonating explosive.

The invention will be further described in connection with the drawings in which:

Figure 1 is a cross sectional view of a specific delay electric blasting cap which has an average delay period of about 40 milliseconds.

Figure 2 is an elevation, partly in section, of a specific delay electric blasting cap which has an average delay period of about 115 milliseconds.

Referring to Figure 1, into a drawn gilding metal shell 0.260 inch in inside diameter and approximately 0.007 inch thick represented by 10, a base charge 12 of tetryl, a primary detonator charge 14 of nitromannite, and a flash charge 16 composed of 75% diazodinitrophenol and 25% nitromannite are pressed in conventional manner under an inner capsule 18. A brass delay tube 20, $\frac{1}{16}$ inch high, is pressed in tight fitting engagement into shell 10 above inner capsule 18. Delay tube 20 is provided through its center with a $\frac{1}{64}$ inch diameter bore 22 into which is pressed a charge 24 of 0.04 gram of granular 30—96 mesh black powder of 1.84

to 1.87 grain density, under 450 pounds pin pressure (31,000 pounds per square inch) to a height of 0.068 inch. A conventional electric match ignition assembly is located over delay tube 20. This assembly is composed of insulating tube 26 into which sulphur 28 is cast around electric match 30 bearing copper acetylidy type match head 31 and to which are attached leg wires 32 and 34 which are insulated above their point of attachment to electric match 30. Over this ignition assembly are two poured sealing plugs, 36 of asphaltic material and 38 of sulphur. Shell 10 is provided with conventional bead 44 which assists in anchoring the sealing plugs. The space shown around match head 31 and in bore 22 above delay train 24, amounts to about 0.16 cc.

In the operation of the cap shown in Figure 1 a current is passed through leg wires 32 and 34 to electric match 30, firing match head 31, the flame from which ignites black powder train 24 which in turn initiates flash charge 16 to cause detonation of the cap. These delay caps are found to have a delay period averaging about 40 milliseconds and a standard deviation of about 16 milliseconds.

Standard deviation is a statistical term which is a measure of the dispersion of values about an average. Specifically it is the root mean square deviation, or in mathematical terms

$$\sqrt{\frac{\sum d^2}{n}}$$

where "d" is the deviation of each specimen of a sample from the average and "n" is the number of specimens in the sample.

The standard deviation of the caps just described was determined by firing 419 of the initiators, averaging the delay times obtained, and calculating the root mean square deviation of the delay times from the average delay time.

Their standard deviation is a particularly valuable characteristic of the caps of this invention. It can be shown by statistical methods that the difference in firing time between any two of the present caps picked at random will be expected in about 90% of the cases to be greater than 0.18 multiplied by the standard deviation and in about 90% of the cases to be less than 2.3 multiplied by the standard deviation. Co-pending application Serial Number 670,193, filed May 16, 1946, by David M. McFarland, for "Process of Blasting" discloses that peculiarly desirable effects are obtained when adjacent explosive charges are set off within from about 2 to about 150 milliseconds of one another. Consequently, in accordance with the above principles, these desirable effects may be expected to be substantially obtained when delay electric blasting caps having standard deviations between about 11 milliseconds

$$\left(\frac{2}{0.18} \right)$$

and about 65 milliseconds

$$\left(\frac{150}{2.3} \right)$$

are employed in a row of bore holes. Caps of the present invention provide standard deviations within this range. A discussion of the statistical principles involved will be found in Simon's "Engineers' Manual of Statistical Methods," John Wiley & Sons, Inc., New York, 1941.

Without limiting the invention to any theory

of operation, it may be pointed out that the delay electric blasting caps of this invention appear to function by a combination of two actions both of which depend upon ventless construction. Under the closed conditions, the heat and gas production from the burning elements develop high gas pressures in the caps. Since deflagrating delay powders burn more rapidly under high pressure conditions, longer delay trains may be employed than would otherwise produce the desired short delay periods. With longer delay trains, flashing through the delay trains is prevented and more consistent timing may be obtained. The high gas pressures developed also tend to force the burning delay trains out of the bores of delay elements, when they are employed, and into the detonating explosives. Such blowing out of delay trains is of course undesirable until the desired delay times have been obtained. In the present caps the high consolidation of the delay powders in the bores of the delay elements causes the trains to resist blowing out for a time sufficient to provide the desired delay. However, after the delay trains have burned away a sufficient amount of delay powder, and after pressures have built up sufficiently high, the remaining portions of the delay trains are blown down into the detonating explosives insuring cap detonation. Thus it may be seen that in the present delay caps the delay period appears, at least in part, to be caused by a sort of valve action wherein the delay train acts as a plug holding back the initiating force from the detonating explosive and then after a period of time releasing so that the burning powder spews into the detonating explosives.

To provide the desired delay action the volume of the space above the delay train should be sufficiently small to permit development of the necessary pressures, but, on the other hand, it should be large enough to prevent bursting of the shell and seal and consequent premature release of pressure.

The cap shown in Figure 2 is in general similar to that shown in Figure 1 except that it is designed for a somewhat longer delay time. Similar parts are numbered similarly in the two drawings. Delay train 24, however, is made up of 0.08 gram of the black powder and reaches to a height of 0.133 inch in the delay tube. Since this larger amount of powder produces considerably more gas than is produced by the delay train in the cap of Figure 1, paper spacer tube 40, $\frac{1}{16}$ inch in height, is inserted between delay tube 20 and insulating tube 26, and shell 10 is made sufficiently long to accommodate this added element. Thus, sufficient space, amounting to about 0.48 cc., is provided for the increased amount of gas produced by the longer delay train. This cap of Figure 2 produces an internal pressure close to that which will force out seals 36 and 38, and for this reason, it is preferred to provide crimp 42 for additional resistance to plug blow-outs.

This initiator of Figure 2 has been found to give an average delay time of about 115 milliseconds and a standard deviation of about 15 milliseconds.

Delay electric blasting initiators having other delay periods than those obtained according to the specific embodiments just described may be made by varying the delay train length and by varying the amount of free space in communication with the delay train and with the ignition element. The invention will be found applicable to the production of caps having average delay

periods as low as about 10 milliseconds and as high as about 250 milliseconds.

It is of assistance to the proper functioning of the caps of the type just described that there be a tight joint between the delay tube and the shell walls. Otherwise, it may sometimes be found that the flame from the ignition element bypasses the delay train and directly ignites the explosives in the base of the cap. Usually it is preferred to obtain a tight seal, as in the specific embodiments described above, by means of a press fit between the delay tube and the initiator shell.

As has been stated above, the delay powder should be highly consolidated. It has been found that to obtain the delay periods desired in accordance with the invention, the delay trains should usually be consolidated under pressures of at least approximately 7,000 pounds per square inch, and preferably at pressures above about 10,000 pounds per square inch. Consolidation pressures as high as about 40,000 pounds per square inch have been successfully employed and while higher pressures may be used provided that the delay powder is not pressed beyond the point where it will ignite, it is usually not necessary to use them. It is to be noted that the delay powders are separately consolidated to avoid the application of high pressures to the detonating explosives. This consolidation of the delay train is not only important to the obtention of sufficient delay times but also to the obtention of consistent delay times. Some variation in delay times may be obtained by variation in the consolidation pressures employed, the higher consolidation pressures producing longer delay times.

The cross sectional area of the delay train and its height generally contribute to the obtention of consistent delay times. If the cross sectional area of the delay train is greater than about 0.05 square inch, the timing may tend to be erratic, and to obtain consistent timing and sufficient retention of the delay powder in the tube, it has been found that heights of delay powder of at least about $\frac{1}{2}$ inch are often necessary.

The delay tube is preferably made of metal but other rigid materials may be used, it being desirable that the delay tube be sufficiently rigid so that the delay powder will remain adequately consolidated in the bore. Often, and particularly with the wider bore diameters, it is found desirable to constrict the lower end of the bore slightly as by providing the bore with a slight taper or with a small shoulder at its base. Thus bore 22 in the delay tubes shown in the drawings has a diameter of about 0.141 inch at its top below the flaring portion and about 0.138 inch at its base. A constricted bore makes for consistent delay times as it reduces variations in the time at which the delay powder will be blown from the delay element.

As has been outlined above the volume of space in the cap in communication with the gas-producing elements is important since it determines the pressure under which the delay train burns and a high pressure is necessary to obtain blowing out of the delay train and to obtain burning speeds sufficient that enough delay powder can be used to obtain consistent timing. It will be apparent that the spacing in the initiators shown in the drawings should be varied if other types of delay powder are used or if other times are desired.

The sealing means and the shells employed

should be sufficiently strong that the pressures built up inside the initiators are resisted until after the delay action has taken place. It is readily apparent that many different types of seals may be used, and those shown in the drawings are only illustrative. For instance, rubber plugs crimped into the initiator shells make excellent seals.

The invention may be practiced with different types of propellant powders. As examples of propellant powders, in addition to the black powder employed in the specific embodiments described above, may be mentioned other granulations and densities of black powder, or smokeless powder of the single base or double base variety in either grain or stick form. More specifically a delay initiator having an average delay time of about 40 milliseconds may be prepared by pressing 0.05 gram of 18 mesh single base smokeless powder under 400 pounds pin pressure (28,000 pounds per square inch) into the delay tube of Figure 2 to a height of $\frac{1}{2}$ inch.

In some instances and particularly when delay electric blasting caps of the present invention are to be prepared having delay times near the upper end of the range, propellant delay powders may be mixed with inert materials or slower burning materials prior to consolidating them in the delay trains. Conversely, accelerating materials may be incorporated when the shorter period delay caps are to be prepared.

It will also be readily apparent that the invention is applicable to caps of many different sorts. For example, shells of different materials such as aluminum or plastic compositions may be used provided they are sufficiently strong to resist bursting before desired delay times are attained. Also many different explosive materials with or without inner capsules may be used in the initiators of the invention. For example, trinitrotoluene or pentaerythritol tetranitrate base charges may advantageously be used, as may diazodinitrophenol or lead azide primary detonator compositions and various flash charges such as mercury fulminate may also be employed. If preferred the flash charge may be eliminated with some primary detonator compositions, or the invention may be used with single charge initiators.

Similarly many types of ignition compositions may be used such as lead styphnate or diazodinitrophenol. Even gasless ignition elements may be employed providing the space in the cap in communication with the combustible delay train is made sufficiently small to compensate for any reduction in the amount of gases produced. It also is readily seen that the invention is applicable to different types of ignition elements as, for example, the bridge plug type or the bead type commonly employed in electric blasting caps.

What is claimed is:

1. A delay electric blasting cap comprising a ventless shell, a detonating explosive in said shell, a deflagrating electric ignition element in said shell, a charge of deflagrating propellant powder selected from the group consisting of black powder and smokeless powder consolidated under a pressure of at least approximately 7,000 pounds per square inch and positioned in plug-like engagement within a passageway between said detonating explosive and said ignition element, means defining an enclosed space in communication with said deflagrating propellant powder on the side thereof away from said detonating explosive, the volume of said space and the amount of said de-

flagrating propellant powder providing, upon burning of said ignition element and said deflagrating propellant powder, detonation of said cap between about 10 milliseconds and about 250 milliseconds of the time of firing said ignition element, a seal closing said shell, and said shell and said seal having a strength sufficient to prevent their bursting prior to the detonation of said cap.

2. A delay electric blasting cap according to claim 1 in which the ignition element is positioned to initiate directly deflagration of said deflagrating propellant powder.

3. A delay electric blasting cap comprising a ventless shell, a detonating explosive in said shell, a deflagrating electric ignition element in said shell, a rigid tubular element fitting tightly in said shell and positioned between said detonating explosive and said ignition element, a deflagrating propellant powder selected from the group consisting of black powder and smokeless powder in plug-like engagement in said tubular element consolidated under a pressure of at least approximately 7,000 pounds per square inch, means defining an enclosed space in communication with said deflagrating propellant powder, the volume of said space and the amount of said deflagrating propellant powder providing, upon burning of said ignition element and said deflagrating propellant powder, detonation of said cap between about 10 milliseconds and about 250 milliseconds of the time of firing said ignition element, a seal closing said shell, and said shell and said seal having a strength sufficient to prevent their bursting prior to detonation of said cap.

4. A delay electric blasting cap according to claim 3 in which the deflagrating propellant powder is black powder.

5. A delay electric blasting cap comprising a ventless shell, a detonating explosive in said shell, a deflagrating electric ignition element in said shell, a rigid tubular element fitting tightly in

said shell and positioned between said detonating explosive and said ignition element, a charge of black powder in plug-like engagement in said tubular element consolidated under a pressure of at least approximately 7,000 pounds per square inch to a height of at least approximately $\frac{1}{2}$ inch, means defining an enclosed space in communication with said black powder, the volume of said space and the amount of black powder providing, upon burning of said ignition element and said black powder, detonation of said cap between about 10 milliseconds and about 250 milliseconds after the firing of said ignition element, a seal closing said shell and said seal and said shell being sufficiently strong to prevent their bursting prior to detonation of said cap.

6. A delay electric blasting cap according to claim 5 in which the bore of said tubular element is smaller at its base than at its top.
